DES 452

Des. 452

Anthony J. Gallagher & John J. Baker
Letters Patent No 452 Dated April 20th 1852 Ante-dated Jan 17, 1852.

The schedule referred to in these Letters Patent and making part of the same.

To all whom it may concern.

Be it known that we Anthony J. Gallagher and John J. Baker (trading) under the firm of Gallagher & Baker of the City and County of Philadelphia and State of Pennsylvania have invented or produced a new and original design for Cooking Stoves, and we do hereby declare that the following is a full and exact description of the same.

The design consists of a combination of ornaments as represented in the accompanying drawings.

Fig 1 is a side elevation of the stove with its ornaments

Fig 2 is a front elevation of the stove with its ornaments

Fig 3 is a back elevation of the stove

Letter A fig 1 is the ornaments of the baking oven door

" B " 1 is the ornaments of the fire box door

" C " 1 is the ornaments of the side of the roasting oven

" E " 2 is the ornaments of the lower front of the stove

What we claim as our invention and wish to secure by letters patent is the application of the above design to Cooking Stoves.
